CLAIM

The ornamental design for a hanger with clips for hats, as shown and described.

DESCRIPTION

FIG. 1 is a perspective view of a hanger with clips for hats showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines throughout the figures depict portions of the hanger with clips for hats that form no part of the claimed design.

The hanger with clips for hats is shown with a symbolic break in its length. The appearance of any portion between the break lines forms no part of the claimed design.
